(57) **CLAIM**

The ornamental design for a bookshelf with a cover holding ledge, as shown and described.

DESCRIPTION

FIG. 1 is a perspective view of the invention;

FIG. 2 is a top plan view of the invention shown in FIG. 1; FIG. 3 is a front elevational view of the invention shown in FIG. 1;

FIG. 4 is a right side elevational view of the invention shown in FIG. 1;

FIG. 5 is a left side elevational view of the invention shown in FIG. 1;

FIG. 6 is a bottom plan view of the invention shown in FIG. 1; and,

FIG. 7 is a rear elevation view of the invention shown in FIG. 1.

1 Claim, 4 Drawing Sheets

FIG. 1

FIG. 2

FIG. 3
